ATTORNEY.

UNITED STATES PATENT OFFICE.

LEON CAMMEN, OF NEW YORK, AND AUGUST W. OFELDT, OF WEEHAWKEN, NEW JERSEY, ASSIGNORS TO NORTHWIND SPARK PLUG CORPORATION, OF NEW YORK, N. Y., A CORPORATION OF DELAWARE.

SPARK-PLUG.

1,344,172.

Specification of Letters Patent. Patented June 22, 1920.

Application filed August 6, 1919. Serial No. 315,640.

To all whom it may concern:

Be it known that we, LEON CAMMEN, citizen of the United States, and resident of borough of Manhattan, in the city, county, and State of New York, and AUGUST W. OFELDT, citizen of the United States, and resident of Weehawken, Hudson county, State of New Jersey, have invented certain new and useful Improvements in Spark-
10 Plugs, of which the following is a specification.

Numerous attempts have been made in the past years to produce a spark plug with internal cooling of the center electrode by
15 a flow of air admitted from the outside on the suction stroke but practically all these attempts have failed for the following reasons.

In the first place, the center electrode
20 needs cooling especially when the engine is running at the heaviest load, as in tractor work when the tractor is pulling, or in car work on hills or when the car is running at high speed. But just then the vacuum
25 in the cylinder is low, and only little air can enter through the air valve in the spark plug. Had all this air been used for the cooling of the center electrode, it would do good, but in all constructions suggested
30 hitherto, the air was admitted simply to the center chamber of the spark plug, and only a very small part of it came in direct contact with the center electrode. Therefore the amount of cooling produced was
35 insignificant.

In the second place, ball check valves were used to control the admission of air on the suction stroke, and its exclusion on the pressure and explosion parts of the cycle. Ex-
40 tensive tests made by me have shown that the action of the ball is too slow for this purpose, and that is a tendency on the explosion stroke for the hot gases to blow past the ball. As a result of this the entire
45 plug gets very hot.

These sources of trouble have been obviated in the construction set forth here.

In the drawings,

Figure 1 shows a section through the
50 plug;

Fig. 2 shows a side view of the air inlet nut 3; and

Fig. 3 shows a top view of the same
nut 3.

In the spark plug shown, 1 is the shell, 55
2 the insulator, shown here as porcelain, but which may also be of mica, lava, or any other suitable material, 4 is the tightening lock-nut the duty of which is to hold the insulator in place. These parts are common to 60 all spark plugs now on the market.

The shell 1 terminates in a plate electrode 6, a construction which is not new in itself. The center electrode 5 is in this case built as a tube having a central passage 7, said 65 central passage opening at one of its ends into a chamber provided for this purpose in the air inlet nut 3, and its other end, as at 8, into the central chamber of the spark plug 9. At that end the center electrode 70 ends in a solid piece 10 which may be either formed as an integral part of the tube, or attached to it in any of various ways, as by welding, or screwing in.

The purpose of this construction is to 75 provide means for preventing the fouling of the plug by oil. As will be shown below, air enters into the passage 7 of tube 5 during the suction stroke of the cylinder. At 8 it passes into the center chamber 9 of the 80 spark plug, and has to pass through the annular passage 11 in order to egress therefrom. While doing so, it blows away any oil that might have settled in 11, and prevents its accumulation and carbonization. 85

The air inlet nut is provided with several holes or slots 12, by which, and the passage 13 in the top nut 14 it communicates with the external atmosphere. In its upper (in the position shown in the drawing) part 90 it is provided with a slight bulge 15 over which lies the disk valve 17 which is simply a thin round disk of hard metal, such as bronze or steel.

When the engine is not operating; or during the suction stroke, air can enter freely through passage 13 in the top nut 14, and flow around the disk valve 17 into slots 12 and tube 5. On the compression and explosion strokes, however, the air pressure 100 from inside forces the disk valve 17 against the carefully machined or ground seat 16 in the top nut 14.

Numerous tests have shown that there is a very definite range of movement for the 105 valve 17 in a spark plug during which it will operate. If the distance through which the valve is permitted to move is too small,

not enough air will be admitted to do good, and if it is too great, the movement of the valve becomes excessively slow, and a leak of compression and gases of combustion result, causing loss of power and overheating of the valve. Tests have shown that the best results are secured when the disk valve 17 has a freedom of movement of the order of 0.001 inch while very poor results were obtained with the valve having a freedom of motion of 0.005 in., except on very high speed high compression engines.

Variations may be resorted to within the spirit and scope of my inventions, and some parts thereof used without others.

I claim:

1. In a spark plug, a tubular center electrode and a disk valve to admit air to said electrode, and to prevent said admission of air when the pressure in the center tube electrode is greater than atmospheric.
2. In a spark plug, a tubular center electrode and a disk valve to admit air to said

electrode when the engine is not running, but to prevent said admission of air from outside of the engine when the pressure in the center tube electrode is greater than the atmospheric.

3. In a spark plug, a tubular center electrode, and a disk valve admitting air to said center electrode when the engine is not running, but preventing said admission of air from the outside of the engine when the pressure in the center tube electrode is greater than the atmospheric pressure, the valve being held against its seat by said difference of pressure.

4. In a spark plug, a disk valve to regulate the admission of air to the interior of the plug chamber, said valve having a freedom of motion of the order of 0.001 inch.

Signed at New York, in the county and State of New York, this 4 day of August A. D. 1919.

LEON CAMMEN.
AUGUST W. OFELDT.
